UNITED STATES PATENT OFFICE.

RUDOLPH JOSEPH ALTGELT AND CHARLES FREDRIK CARLSON, OF SOUTH BEND,
INDIANA, ASSIGNORS TO OLIVER CHILLED PLOW WORKS, OF SOUTH BEND,
INDIANA.

PLOW.

1,082,672.

Specification of Letters Patent. Patented Dec. 30, 1913.

Application filed June 25, 1913. Serial No. 775,751.

To all whom it may concern:

Be it known that we, RUDOLPH J. ALTGELT and CHARLES F. CARLSON, of South Bend, in the county of St. Joseph and State of Indiana, have invented certain new and useful Improvements in Plows; and we do hereby declare the following to be a full, clear, and exact description of the invention, such as will enable others skilled in the art to which it appertains to make and use the same.

This invention relates to plows and more particularly in the construction of the soil-engaging portion or "plow bottom" which comprises the mold-board, share and land-side,—one object of our present invention being to provide simple and efficient means whereby the share may be quickly and securely applied to the standard or frog and to the mold board, or easily and quickly removed therefrom.

With this and other objects in view the invention consists in certain novel features of construction and combinations of parts as hereinafter set forth and pointed out in the claims.

In the accompanying drawings, Figure 1 is a plan view of a plow embodying our improvements; Fig. 2 is a side elevation; Fig. 3 is a sectional view illustrating the connecting means for the share to the mold-board and standard, and Fig. 4 is a separate view of the share.

1 represents a standard or frog which may be conveniently made approximately V-shaped in cross section so as to form two wings or members 2, 3 to which the soil-engaging members, constituting the plow bottom, are secured, said plow bottom comprising a mold board 4, a share 5 and a land-side 6. The mold board 4 is secured to the wing 2 of the standard or frog 1, and its forward edge is beveled, as shown at 7. The share 5 is also secured to the wing 2 of the standard and its upper or rear edge is beveled, as at 8, to overlie the beveled forward edge 7 of the mold board and thus prevent the latter from springing upwardly.

For the purpose of securing the share in place and permitting its easy and quick application or removal, the devices now to be described are employed: Several lugs 11 (preferably three) are securely bolted to the under face of the share and provided with offset or hooked ends 12 which underlie and

project slightly beyond the upper beveled edge of the share. For the accommodation of some of these lugs (preferably two), the wing 2 of the standard is provided with holes 13, so that when the share is being placed in position as shown in dotted lines in Fig. 3, the hooked-ends 12 of the lugs 11 will pass through said holes and assume the position shown in full lines, with the upper faces of ends 12 of said lugs bearing against the inner face of the wing 2 of the standard and the body portions of said lugs disposed in the holes 13. For the accommodation of the upper lug on the share, a plate 14 is secured to the under face of the mold board and projects beyond the edge thereof,—said upper lug bearing the same relation to the plate 14 as the other lugs bear to the perforated portions of the standard. The fastening devices above described form, in effect, a hinge connection for the share, enabling the latter to be readily dropped or swung into place or lifted or swung out of position.

When the share has been attached to the standard and mold board as above described, it may be locked in position by a bolt 15 passing through the share and the wing 2 of the standard. The share 5 is constructed without a rearwardly projecting flange or gunnel heretofore commonly employed, and it may therefore be termed a gunnelless share. Instead of employing a flange or gunnel, we weld a patch 16 (having a shoulder 17) under the forward portion of the share, said patch having a shape substantially as indicated in dotted lines in Figs. 1 and 4 and extending rearwardly beyond the lower or forward end of the standard so as to overlie the latter and extending forwardly approximately to the point of the share. The patch 16 thus serves to thicken the forward portion of the share and reinforce or strengthen the same where the greatest strain and wear are brought to bear. The provision of the patch or thickened portion of the share serves also to effect a raising of the scouring surface of the share above the standard so as to present a straighter or less concave scouring surface than is accomplished with a share having a flange or gunnel.

The bolt 15 is passed through the reinforced or thickened portion 16 of the share and through the wing 2 of the standard.

This bolt serves the same purpose as the gunnel bolt of a gunnel share, but the nut on this bolt is more accessible than is the nut on a gunnel bolt, because with a gunnel share, especially on engine and heavy wheeled plows, it is difficult to raise the plow high enough off the ground to get under the same conveniently with a wrench. The landside 6 is secured to the wing 3 of the standard and projects forwardly under the share to the shoulder 17 so as to assist in supporting said share, and the latter is recessed at 18 to receive the landside.

We do not, in this case, claim the above-described construction of share and its relation to the landside and standard, the same being the subject matter of claims presented in our copending application, filed even date herewith.

Having fully described our invention what we claim as new and desire to secure by Letters-Patent, is:—

1. The combination with a standard having holes near one edge, a mold board secured to the standard, and a share, of lugs secured to the under face of the share and having hooked-ends projecting beyond the edge of the share, said lugs entering the holes in the standard and their hooked ends engaging the inner face of the latter.

2. The combination with a standard having holes, a mold board secured to the standard, and a share, of a plurality of lugs secured to the share and adapted to enter the

holes in the standard, each of said lugs having a hooked end to engage the inner face of the standard, a perforated plate secured to the mold-board and projecting beyond the edge thereof, and a lug secured to the standard and entering the perforation of the plate, said lug having a hooked end to engage the rear face of the plate.

3. The combination with a standard having holes, a mold board secured to the standard, and a share, of lugs secured to the share and adapted to enter the holes in the standard, each of said lugs having a hooked end to engage the inner face of the standard, and a bolt passing through the share and the standard.

4. The combination of a standard having holes, a mold board secured to the standard and having a beveled forward edge, a share having a beveled edge overlying the beveled edge of the mold board, lugs secured to the share and entering the holes in the standard, said lugs having hooked ends to engage the inner face of the standard, and a bolt passing through the share and standard.

In testimony whereof, we have signed this specification in the presence of two subscribing witnesses.

RUDOLPH JOSEPH ALTGELT.
CHARLES FREDRIK CARLSON.
